LIQUID STERILIZER AND DISPENSER

David Free, West Vancouver, British Columbia, and William A. Shand and Wolfgang Scherrelies, Vancouver, British Columbia, Canada, assignors to Naturvard Research (Canada) Ltd., Vancouver, British Columbia, Canada

Filed Apr. 29, 1974, Ser. No. 465,132

Claims priority, application Canada Feb. 15, 1974

Term of patent 14 years

Int. Cl. D23—01

U.S. Cl. D23—3

FIG. 2

FIG. 1

FIG. 1 is a perspective view taken from the front, top and right side of a liquid sterilizer and dispenser showing our new design, the rear being the same as the front shown but without the oval housing and spigot; and

FIG. 2 is a left side elevational view thereof.

We claim:

The ornamental design for a liquid sterilizer and dispenser, substantially as shown and described.
